UNITED STATES PATENT OFFICE.

JOHN EDWARDS BARBOUR, OF PATERSON, NEW JERSEY.

STRAND PACKAGE.

Application filed April 27, 1925. Serial No. 26,030.

The object of this invention is to provide a twine or the like package for use by carpet workers and others using twine in sewing in which the twine will not only be in standard 5 lengths but from which the user can readily detach the lengths or strands one by one as he needs them without snarling the package.

In the accompanying drawing,

Fig. 1 is a plan view illustrating the package diagrammatically, only one of the two 10 counterpart end portions of the package, which may be of any length, being shown; and

Fig. 2 is a magnified view of one of the 15 strands, with intermediate portions thereof broken away.

a indicates the strands of twine or other filamentous material suitable for use in sewing, this invention not being specifically concerned with the material of the strands, so 20 long as they are freely flexible. They are all approximately of the same length, say three or four feet.

The strands exist in the package braided 25 together loosely, as shown diagrammatically in Fig. 1, and so that the ends of all the strands approximately coincide with each other. The braiding is indicated at *b* in Fig. 1 and in the present case extends from 30 a transverse line (approximately at *c*) removed from the end of the package shown in said figure to a corresponding line the same distance from the other end of the package (not shown in the drawing), the absence of 35 a braided condition at the extreme end portions of the package being due to the impossibility of maintaining the braiding clear to the ends of the package even if it were actually carried out to that extent.

40 It is an important feature of the invention that the strands be loosely braided, since otherwise in the effort to withdraw a single strand it will exert a dragging influence on the others and this will produce a snarling 45 of the strands in the package, even if the strand to be withdrawn is grasped at a point intermediate its length (instead of at one end) and pulled on in that way.

To facilitate removal of the strands one 50 by one, both with respect to singling them out and reducing the tendency of the strand which it is intended to remove dragging along others with it and so producing a snarling, the braiding is preferably effected 55 with respect to flat or band-like groups of

the strands. That is, the strands are arranged first in groups, in each of which all the strands are side by side in the same plane and have their ends substantially coinciding, and then these band-like groups are braided 60 together. This is the condition actually shown in Fig. 1 of the drawing. This results in a desirable paralleling of the strands which facilitate singling them out and it reduces the bends in each strand and consequently the binding point of each strand on the others and thus minimizes the tendency of any strand to drag others out with it when it is itself pulled upon to withdraw it. I 65 have said that the ends of the strands approximately coincide, and this is true also of the ends of the strand groups. But I do not wish to convey that there is necessarily alinement or even approximate alinement of such 70 ends across the package, as appears in Fig. 1. 75

It will be understood that the pattern of the braiding is entirely immaterial, although the simple pattern shown is preferred because it facilitates the individual removal of 80 the strands.

When the package has been formed as described, one or both ends thereof (preferably both ends) are subjected to a singeing treatment if the strands are formed of fibrous material. This leaves all the ends in transverse alinement and at the same time removes the fibres of all the strands at their ends by a single operation, the result of removing the fibres being to permit each strand to be readily threaded through the 85 eye of a needle by the user. Fig. 2 shows at *d* the end of a strand *a* (magnified) singed in this manner and thus more or less charred and thus pointed. As to this part of the invention it is not broadly material whether 90 the strands be braided or otherwise intertwined to produce a unitary mass of them, but it is important that the intertwined mass be a band that is flat because that facilitates 95 the performance of the fibre-eliminating step 100 and insures uniformity of the results of that stem.

Having thus fully described my invention what I claim and desire to secure by Letters 105 Patent is:

1. A strand package comprising groups of freely flexible strands of approximately equal lengths, the strands in each group having their ends at each end of the group all approximately in coincidence with each 110

other, and the groups being loosely braided together and having their ends all approximately in coincidence with each other.

2. A strand package comprising band-like groups of freely flexible strands of approximately equal lengths, the strands in each group having their ends at each end of the group all approximately in coincidence with each other, and the groups being loosely braided together and having their ends all approximately in coincidence with each other.

3. The method of forming a package of fibrous strands which consists in intertwining the strands with each other in the form of a flat band and so that at one end of the

band thus formed the ends of the strands will approximately coincide with each other and finally eliminating fibrous projections by a single operation from all said strand ends at one end of the package.

4. The method of forming a package of fibrous strands which consists in intertwining the strands with each other in the form of a flat band and so that at one end of the package thus formed the ends of the strands will approximately coincide with each other and finally by a single operation pointing the strand ends at one end of the package.

In testimony whereof I affix my signature.

JOHN EDWARDS BARBOUR.
